UNITED STATES PATENT OFFICE

132,978

DESIGN FOR A DARNING MACHINE OR THE LIKE

William T. Maxant, Ayer, Mass.

Application November 4, 1941, Serial No. 104,027

Term of patent 14 years

To all whom it may concern:

Be it known that I, William T. Maxant, a citizen of the United States, residing at Ayer, in the county of Middlesex and State of Massachusetts, have invented a new, original, and ornamental Design for Darning Machines or the like, of which the following is a specification, reference being had to the accompanying drawings, forming part thereof.

In the accompanying drawings:

Fig. 1 is a side elevation of a darning machine, embodying my new design;

Fig. 2 is a top plan view thereof;
Fig. 3 is an end elevation thereof from one end; and

Fig. 4 is a similar view of the opposite end.

The characteristic features of my design reside in the portions shown in full lines.

I claim:

The ornamental design for a darning machine or the like, substantially as shown and described.

WILLIAM T. MAXANT.
